COLD AIR INLET BOOT FOR AIR-HEATING
FURNACESMerton D. Jones, Kalamazoo, Mich., assignor to
Kalamazoo Stove & Furnace Co., Kalamazoo,
Mich.

Application June 26, 1946, Serial No. 679,332

11 Claims. (Cl. 126—99)

1

This invention relates to improvements in cold air inlet boot for air heating furnaces.

The principal objects of this invention are:

First, to provide a cold air boot for a furnace which may be shipped in a knocked-down form and assembled and attached to the casing of a furnace without the aid of a skilled sheet metal worker.

Second, to provide a cold air boot for a furnace which will present a sloping surface for the attachment of cold air ducts thereto.

Third, to provide a cold air boot for a furnace with novel attaching flanges requiring less bolts than boots used heretofore.

Fourth, to provide a boot which will keep the cold air separated from the furnace casing until the air actually enters the furnace.

Objects relating to details and economies of the invention will appear from the description to follow. The invention is defined and pointed out in the claims.

The drawings of which there is one sheet show a preferred form of the invention.

Fig. 1 represents an elevational view partially broken away, of a furnace having two cold air boots embodying the invention attached thereto.

Fig. 2 represents a cross-sectional view taken along the line 2—2 in Fig. 1.

Fig. 3 represents a perspective cross-sectional view showing the joint between the end wall and top of the boot.

Fig. 4 represents an exploded perspective view showing the various members of the boot.

The drawings illustrate a furnace 1 having a sheet metal casing 2 to which the cold air ducts 3 are attached by the boots generally indicated at 4. Apertures 5 are provided in the casing for the passage of cold air into the bottom of the casing.

The boot 4 consists of flat end walls 6 having outwardly flanged ends 7 defining bolt holes for attaching the boot to the casing. The top, bottom, side and sloping edges of the end walls are formed with inwardly turned flanges 8.

The body of the boot consists of a continuous strip of sheet metal bent to form a top 9, bottom 10, side 11, and upper and lower sloping walls 12 and 13. The upper sloping wall defines an upwardly flanged hole 14 to which the air ducts 3 are connected. The ends of the body of the boot are folded into return bend flanges 15 which are offset inwardly of the body of the boot and out-turned edges 16 substantially in the planes of the body so as to define slots between the edge and the return bend flanges along the edges

2

of the body arranged to receive the flanges 8 on the ends of the boot. The upper and lower ends of the boot are slit into a series of fingers 17 terminating in the body of the boot along arcuate lines of a radius equal to the radius of the furnace casing.

A baffle 18 is provided with downturned flanges 19 which are bolted to the end plates 6 so that the upper edge of the baffle abuts against the junction of the top and upper sloping sections of the body of the boot. The lower end of the baffle is slit into a series of fingers 20 terminating along an elliptical line in the body of the baffle.

In assembling the boot, the flange on one end plate may be slid into the slot on one end of the body and one side of the baffle may be bolted to that end plate. The extending edge 16 of the body may then be bent over the side of the end plate to hold it in place and the other end plate similarly attached. The upper fingers 17 may then be bent downwardly and the lower fingers 17 bent downwardly in an arcuate surface and the boot may be bolted to the side of the casing with the upper fingers 17 outside and the lower fingers 17 inside the opening 5. It will be noted that the ends of the end flanges 15 are cut away as at 21 so that the flanges 7 on the end walls will fit flush against the casing. The fingers 20 on the baffle may then be bent upwardly on the inside of the casing to complete the boot structure.

The baffle 18 serves to direct the cold air to the opening 5 without forming eddy currents in the boot and also leaves a dead air space along the upper part of the boot so that there will be no heating of the air in the boot to hinder the natural draft circulation through the cold air flues and the casing of the furnace.

The parts of the boot may be inexpensively formed from sheet metal and several of the body sections may conveniently be nested together for economical shipment. Installation of the boot does not require any cutting and fitting of parts such as would require the services of an expert sheet metal worker.

The invention has been illustrated and described in an embodiment which has been found highly satisfactory. No attempt has been made to show other possible adaptations, as it is believed that this disclosure will enable those skilled in the art to adapt the invention as may be desired.

Having thus described my invention, what I claim as new and desire to secure by Letters Patent is:

1. The combination with a hot air furnace casing having a cold air inlet opening adjacent the bottom thereof, of a cold air boot positioned on the outside of said casing comprising a pair of laterally spaced apart similar polygonal-shaped end walls flanged at their inner edges for attachment to the side of the casing and having complementary opposed flanges on their other edges, said end walls being disposed with their corresponding edges in parallel relationship and with said opposed flanges facing inwardly toward each other, an integral poly-paneled side wall member including top and bottom panels and intermediate panels, there being an outwardly and downwardly inclined panel adjacent the top panel and provided with a flanged conduit opening, said side wall member corresponding in shape to the outer edges of said end walls and having inset return bend seam elements on its end edges providing laterally facing slots receiving the opposed flanges of said end walls, said seam elements of said side wall member terminating in laterally projecting flanges foldable upon the exterior sides of said end walls, the top panel of said side wall member having a flange at its inner edge abutting the side of the casing in substantially spaced relation to the upper edge of the casing opening, the bottom panel having a down-turned flange at its inner edge engaged within the casing at the lower edge of said opening therein, and a baffle plate disposed in a downwardly and inwardly inclined relation to the casing with its upper edge engaged in the angle of said side wall member constituted by its top panel and said inclined panel having the conduit opening therein, the lower edge of the baffle being engaged with the upper edge of said casing opening, said baffle having outwardly directed flanges on its end edges abutting the interior sides of said side and end walls and secured thereto.

2. The combination with a hot air furnace casing having a cold air inlet opening adjacent the bottom thereof, of a cold air boot positioned on the outside of said casing comprising a pair of laterally spaced apart similar polygonal shaped end walls flanged at their inner edges for attachment to the side of the casing and having complementary opposed flanges on their other edges, said end walls being disposed with their corresponding edges in parallel relationship and with said opposed flanges facing inwardly toward each other, an integral poly-paneled side wall member including top and bottom panels and intermediate panels, there being an outwardly and downwardly inclined panel adjacent the top panel and provided with a flanged conduit opening, said side wall member corresponding in shape to the outer edges of said end walls and having inset return bend seam elements on its end edges providing laterally facing slots receiving the opposed flanges of said end walls, said seam elements of said side wall member terminating in laterally projecting flanges foldable upon the exterior sides of said end walls, the top panel of said side wall member abutting the side of the casing in substantially spaced relation to the upper edge of the casing opening, and a baffle plate disposed in a downwardly and inwardly inclined relation with its upper edge adjacent the side wall member and at the inner side of the conduit opening therein, the lower edge of the baffle being engaged with the upper edge of said casing opening.

3. The combination with a hot air furnace having a cylindrical casing defining a cold air inlet

near the bottom thereof, of a cold air boot positioned on the outside of said casing comprising a pair of laterally spaced apart similar end plates having out-turned vertical flanges secured to said casing and complementary opposed flanges along the other edges thereof, said end walls being disposed with their corresponding edges in parallel relationship and with said opposed flanges facing inwardly toward each other, a body member shaped to conform with the outer edges of said end plates and form a top and bottom section, upper and lower converging sloping sections extending from said top and bottom sections and a side section connecting said sloping sections, said upper sloping section defining an outwardly flanged aperture, the edges of said body member being pressed inwardly of said body member and formed into a return flange and then folded outwardly in the planes of the main portion of the body member so as to form slots arranged to receive the opposed flanges on said end panels, the edges of said body member being folded over the sides of said end panels, and a baffle plate positioned in said boot and secured to said end panels with its upper edge in contact with the body member of said boot adjacent to the junction between said top section and upper sloping section and sloping downwardly to said casing above said inlet, the free edges of said body member and baffle being slit into series of fingers and folded into contact with said casing.

4. The combination with a hot air furnace having a cylindrical casing defining a cold air inlet near the bottom thereof, of a cold air boot positioned on the outside of said casing comprising a pair of laterally spaced apart similar end plates having vertical flanges secured to said casing and complementary opposed flanges along the other edges thereof, said end walls being disposed with their corresponding edges in parallel relationship and with said opposed flanges facing inwardly toward each other, a body member shaped to conform with the outer edges of said end plates and form a top and bottom section, upper and lower converging sloping sections extending from said top and bottom sections and a side section connecting said sloping sections, said upper sloping section defining an outwardly flanged aperture, the edges of said body member being formed into a double return bend forming a slot opening toward the edges of said body member and arranged to receive the opposed flanges on said end panels, the edges of said body member being folded over the exterior sides of said end panels, a baffle plate positioned in said boot with its upper edge spaced from said casing and sloping downwardly to said casing above said inlet, the free edges of said body member and baffle being slit into a series of fingers and folded into engaging contact with said casing.

5. The combination with a hot air furnace having a cylindrical casing defining a cold air inlet near the bottom thereof, of a cold air boot positioned on the outside of said casing comprising a pair of laterally spaced apart similar end plates having vertical flanges secured to said casing and complementary opposed flanges along the other edges thereof, said end walls being disposed with their corresponding edges in parallel relationship and with said opposed flanges facing inwardly toward each other, a body member shaped to conform with the outer edges of said end plates and form a top and bottom section, an upper sloping section extending from said top section and a side section, said upper sloping section de-

fining an outwardly flanged aperture, the edges of said body member being formed into a double return bend forming a slot opening toward the edges of the body member and receiving the opposed flanges on said end panels, the edges of said body member being folded over the exterior sides of said end panels, a baffle plate positioned in said boot with its upper edge spaced from said casing and sloping downwardly to said casing above said inlet.

6. A boot adapted to be mounted on a hot air furnace having a cylindrical casing defining a cold air intake near the bottom thereof, comprising a pair of laterally spaced apart similar end panels having outwardly turned vertical attaching flanges along their back edges, said end walls being disposed with their corresponding edges in parallel relationship and having opposed flanges along their other edges turned inwardly of the boot, said inwardly turned flanges being joined with a continuous body member shaped to conform with the outer edges of said end plates and have parallel upper and lower walls, a vertical side wall, and an upper sloping wall, the edges of said body member being folded to form slots receiving said opposed flanges on said end panels, and a baffle plate secured within said boot and spaced at its upper edge from the free edge of said upper wall and sloping downwardly away from said side wall, said sloping wall forming an inlet opening to said boot.

7. A boot adapted to be mounted on a hot air furnace having a cylindrical casing defining a cold air intake near the bottom thereof, comprising a pair of laterally spaced apart similar end panels having outwardly turned vertical attaching flanges, said end panels being joined with a continuous body member shaped to conform with the outer edges of said end plates and have parallel upper and lower walls, a vertical side wall and an upper sloping wall, the corresponding edges of said end panels being arranged in parallel relationship, the edges of said body member and said end panels being joined by a slot and flange joint, and a baffle plate secured within said boot and spaced at its upper edge from the free edge of said upper wall and sloping downwardly away from said side wall, said sloping wall forming an inlet opening to said boot.

8. The combination with a hot air furnace having a cylindrical casing defining a cold air intake near the bottom thereof, of a boot positioned on the outside of said casing consisting of a pair of laterally spaced apart similar end panels having outwardly turned vertical flanges, said end panels being attached to said casing and being joined with a continuous body member shaped to conform with the outer edges of said end plates and have parallel upper and lower walls and an upper sloping wall, the corresponding edges of said end panels being arranged in parallel relationship, and a baffle plate secured within said boot and spaced at its upper edge from the wall of said casing and sloping downwardly at an acute angle to said upper wall to said casing, the inner free edges of said body member and baffle being slit into series of fingers bent into engaging contact with said casing, said sloping wall forming an inlet opening to said boot.

9. The combination with a hot air furnace casing having a cold air inlet opening adjacent the bottom thereof, of a cold air boot positioned on the outside of said casing comprising a pair of laterally spaced apart similar polygonal-shaped end walls adapted at their inner edge

for attachment to the side of the casing and having complementary opposed flanges on their outer edges, said end walls being disposed with their corresponding edges in parallel relationship and with said opposed flanges facing inwardly toward each other, a poly-paneled side wall member including top and bottom panels and intermediate panels shaped to conform to the outer edges of said end walls, there being an outwardly and downwardly inclined panel provided with a flanged conduit opening, said side wall member having seam elements on its end edges receiving the opposed flanges of said end walls, said seam elements terminating in flanges folded upon the exterior sides of said end walls, the top panel of said wall member being substantially above the upper edge of the casing opening, the bottom panel having down-turned fingers at its inner edge engaged within the casing at the lower edge of said opening therein, and a baffle plate disposed in a downwardly and inwardly inclined relation with its upper edge engaged in the angle of said side wall member constituted by its top panel and said inclined panel having the conduit opening therein, the lower edge of the baffle being engaged with the upper edge of said casing opening.

10. The combination with a hot air furnace casing having a cold air inlet opening adjacent the bottom thereof, of a cold air boot positioned on the outside of said casing comprising a pair of laterally spaced apart similar polygonal-shaped end walls adapted at their inner edges for attachment to the side of the casing and having complementary opposed flanges on their outer edges, said end walls being disposed with their corresponding edges in parallel relationship and with said opposed flanges facing inwardly toward each other, a poly-paneled side wall member including top and bottom panels and intermediate panels shaped to conform to the outer edges of said end walls, there being an outwardly and downwardly inclined panel provided with a flanged conduit opening, said side wall member having seam elements on its end edges receiving the opposed flanges of said end walls, said seam elements terminating in flanges folded upon the exterior sides of said end walls, the top panel of said wall member being substantially above the upper edge of the casing opening, and a baffle plate disposed in a downwardly and inwardly inclined relation with its upper edge engaged with said side wall member between said casing opening and said conduit opening, the lower edge of the baffle terminating adjacent the upper edge of said casing opening.

11. The combination with a hot air furnace casing having a cold air inlet opening adjacent the bottom thereof, of a cold air boot positioned on the outside of said casing comprising a pair of laterally spaced apart similar polygonal-shaped end walls flanged at their inner edges for attachment to the side of the casing and having complementary opposed flanges on their other edges, said end walls being disposed with their corresponding edges in parallel relationship and with said opposed flanges facing inwardly toward each other, a poly-paneled side wall member including an outwardly and downwardly inclined panel provided with a flanged conduit opening, said side wall member having seam elements on its end edges providing laterally facing slots receiving the opposed flanges of said end walls, said seam elements of said side wall member terminating in laterally projecting flanges

foldable upon the exterior sides of the said end walls, the top of said side wall member having fingers at its inner edge abutting the side of the casing in substantially spaced relation to the upper edge of the casing opening, the bottom having down-turned fingers at its inner edge engaged within the casing at the lower edge of said opening therein, and a baffle plate disposed in a downwardly and inwardly inclined relation with its upper edge spaced from said casing, the lower edge of the baffle being engaged with the upper edge of said casing opening.
